UNITED STATES PATENT OFFICE.

ABRAHAM O. SIEGEL, OF NEW YORK, N. Y.

ELECTRIC ILLUMINATED-SIGN APPARATUS.

1,039,828.

Specification of Letters Patent.

Patented Oct. 1, 1912.

Application filed December 9, 1911. Serial No. 664,802.

To all whom it may concern:

Be it known that I, ABRAHAM O. SIEGEL, a citizen of the United States, and residing at New York, in the county of New York and State of New York, have invented certain new and useful Improvements in Electric Illuminated-Sign Apparatus, of which the following is a specification such as will enable those skilled in the art to which it appertains to make and use the same.

This invention relates to what are known as electric illuminated sign devices or apparatus and the invention consists in certain improvements in the construction of devices of this class whereby said construction is simplified and the operation thereof made more effectual; a further object being to provide a sign device or apparatus of the class specified by means of which a brilliant and attractive result is produced and which may be used for the purpose of advertising various kinds and classes of articles for sale; and with these and other objects in view, the invention consists in an electric sign apparatus, constructed as hereinafter described and claimed.

The invention is fully disclosed in the following specification, of which the accompanying drawing forms a part, in which the separate parts of my improvement are designated by suitable reference characters in each of the views, and in which:

Figure 1 is a front view of my improved electric sign device or apparatus; Fig. 2 a diagrammatic view showing the apparatus and the method of wiring the same; Fig. 3 a partial horizontal section on the line 3—3 of Fig. 1 and on the line 3—3 of Fig. 4; and; Fig. 4 a back view of the apparatus with the back part of the casing removed, and with part of the construction broken away.

In the practice of my invention I provide a casing *a* which is preferably circular in form in vertical section and which comprises a drum *a*², a front plate *a*³ and a back plate *a*⁴, said back plate being formed into or serving as a door and being hinged at *a*⁵ and provided with any suitable fastening device at *a*⁶.

Mounted in the casing *a*, in the form of construction shown, are two horizontal supports *b* and *c* forming a large central space *d*, a top space *d*² and a bottom space *d*³. Placed centrally on the support *c* is an upper support *e* in which is mounted one end of a shaft *f*, the front end portion of which

is tubular in form and passes through the front plate *a*³ of the casing *a* and has a bearing therein at *f*². Mounted on the shaft *f* and rotatable therewith is a disk *g* composed of insulating material and the back side of which is provided with circular contact rings *h* and *h*² arranged concentrically as shown, and at one side of the support *e* and at the back of the disk *g* are two upright brush devices *i* and *i*² which are adapted to bear, respectively, on the contact rings *h* and *h*².

The front side of the disk *g* is provided with two binding posts *j* and *j*² which contact with the rings *h* and *h*² and connected therewith are circuit wires *k* and *k*² which pass into the tubular end of the shaft *f* as shown at *f*³, and the front end of the shaft *f* is provided with radial tubular arms *m* with which are connected electric lamp sockets *m*² having detachable incandescent electric bulbs *m*³, and the end of the tube *f* is also provided with a lamp socket *n* having a detachable bulb *n*², and with a reflector *n*³, and the wires *k* and *k*² pass through the arms *m* and supply the electric current to the bulbs *m*² and *n*² in the usual manner as clearly shown in Fig. 2.

The disk *g* is provided with a deep circumferential groove *g*² and mounted at the left of the shaft *f* is an electric motor *o* having a shaft *o*² provided with a grooved wheel *o*³ on which and on the disk *g* is mounted a driving belt *o*⁴.

On the support *b* is placed a battery *p*, one pole of which is placed in electrical connection with the motor *o* by a wire *p*², and a wire *p*³ connects the brush *i*² with the motor *o*, and another wire *p*⁴ connects the brush *i* with one terminal *p*⁶ of a switch *p*⁵, and a wire *r* is connected with the other pole of the battery *p* and with the other terminal *p*⁷ of the switch *p*⁵. It will be seen that the switch *p*⁵ is at the top of the casing *a*, in the construction shown, but said switch may be placed in any desired position. The front of the casing *a* is also provided with an annular flaring reflector *s* and, in practice, any suitable advertisement may be placed on the front of the casing, or on the plate *a*³ as shown in Fig. 1.

From the foregoing description it will be seen that the electric bulbs *m*² and *n*² are in a circuit adapted to be opened and closed by the switch *p*⁵ and this circuit also involves the motor *o* and when the switch *p*⁵

is closed the motor will be started and the current will pass from one pole of the battery, through the wire r , the switch p^e , the wire p^i , the brush i , the ring h , the contact j , the wire k , through the lamps m^3 , n^2 , m^3 and back through the wire k^2 , the contact j^2 , the ring h^2 , the brush i^2 , the wire p^3 , through the motor o and back through the wire p^2 to the battery and the shaft f , the disk g , the arms n , and the lamps m^3 , n^2 together with the reflector n^2 will be rapidly rotated and this operation will continue until the switch p^e is again opened.

Although I have described my improvement as an advertising device or apparatus, it will be understood that the same may be employed for various other purposes, such as exhibiting pictures, and instead of using a single circuit as shown and described, two circuits may be employed and any suitable switch device may be substituted for that shown and described herein and other changes in and modifications of the construction described may be made, within the scope of the appended claims, without departing from the spirit of my invention or sacrificing its advantages.

It will also be understood that my invention is not limited to the use of the casing a , as a sign or display member of any kind may be employed and the other parts of the apparatus, including the motor o and battery p may be supported in any desired manner, the object of employing the casing in which the operative parts are mounted being to make the device portable and capable of being placed in any desired position.

Having fully described my invention, what I claim as new and desire to secure by Letters Patent, is:—

1. In an electric display apparatus, a casing or support having a stationary display member at the front thereof, a tubular rotatable shaft mounted centrally in said casing and passing forwardly through said display member and provided in front thereof

with radial arms, a grooved disk mounted on said shaft within said casing and rotatable with said shaft and provided on its back surface with two concentric rings, 50 brushes supported adjacent to said disk and adapted to bear on said rings, binding posts connected with the front of said disk and in contact with said rings, circuit wires connected with said binding posts and passing into said shaft and forwardly therethrough and through said arms, electric lamps connected with said arms and with the front end of said shaft, and means for turning said disk and said shaft. 55

2. In an electric display apparatus, a casing or support having a stationary display member at the front thereof, a tubular rotatable shaft mounted centrally in said casing and passing forwardly through said display member and provided in front thereof with radial arms, a grooved disk mounted on said shaft within said casing and rotatable with said shaft and provided on its back surface with two concentric contact 65 rings, brushes supported adjacent to said disk and adapted to bear on said rings, binding posts connected with the front of said disk and in contact with said rings, circuit wires connected with said binding posts and 70 passing into said shaft and forwardly therethrough and through said arms, electric lamps connected with said arms and with the front end of said shaft, and means for turning said disk and said shaft, consisting 75 of a motor mounted in said casing and the shaft of which is provided with a pulley and a belt passing around said disk and said pulley.

In testimony that I claim the foregoing 85 as my invention I have signed my name in presence of the subscribing witnesses this 8th day of December 1911.

ABRAHAM O. SIEGEL.
